UNITED STATES PATENT OFFICE

JULIAN A. GILES, OF DERBY, CONNECTICUT

WRENCH

Application filed July 17, 1929. Serial No. 378,874.

This invention relates to wrenches, the object of which, among other things, is to provide a wrench of simple construction and great strength, that is adapted to be used in places where the space for the movement of a wrench is limited, where the handle of the wrench will extend substantially parallel with the jaws instead of at right angles thereto, as in general practice, wherein the wrench 10 will have the maximum capacity with the minimum length of movable jaw, so arranged that the strain upon the jaw adjusting mechanism is reduced to the minimum and practically no strain upon the support therefor, 15 and in these and other ways produce a wrench having the maximum efficiency.

To these and other ends, my invention consists in the wrench having certain details of construction and combinations of parts, as 20 will be hereinafter described and more particularly pointed out in the claims.

In the drawings, reference to which is hereby made, and wherein like numerals of reference indicate like parts in the several figures;

Figure 1 is a side view of my improved wrench, with a portion of the handle removed;

Figure 2 is an edge view thereof;

Figure 3 is a fragmentary sectional view thereof, the parts in section being taken generally upon the line 3—3 of Figure 2; and

Figure 4 is a similar view with the movable jaw, worm and adjacent parts in different relative positions.

In the embodiment of my invention as disclosed in the drawings, wherein is disclosed one of the numerous forms that my invention may assume, 10 indicates the head portion 40 having two cheek portions 12—12, separated by an open space 13 that extends at one end to form the lip portions 14, and 11 is the handle which projects therefrom. Between the lip portion 14—14 a fixed jaw 15 is 45 cured by a pin 16 or the like.

The movable jaw 17 is provided with a tail piece 18 at substantially a right angle to the toothed portion and has a fulcrum lug 19 near one end at one side and a plurality of teeth 20 upon the opposite side. In one face of the tail piece is a recess 21, into which projects the head of a stud 22 or the like, which during the free movement of the jaw 17 prevents its disengagement from the head portion 10.

Each cheek of the head portion is provided with an opening 23 located opposite each other and journaled in the head adjacent thereto, and between the cheeks upon the pintle 25 is a roll 24, preferably having a concaved face substantially as shown in Figure 2. I prefer a roll, as 24 or the like, but such is not essential to the operation of my wrench, as a rigid cylindrical member might be substituted therefor or the head portion 55 may be formed with a rounded surface at this point.

The worm 26 has a conical head 27 and a cylindrical bore 28 for a portion of its length to receive the shank 29 of a supporting member 30 which is in part between the cheeks 12 and prevented from passing therethrough by the stud 32.

Within the opening in the shank 29 is a spring 31 which abuts against the bottom of 75 the bore 28 and exerts its tension so as to move the worm 26 toward the roll 24.

The only strain against the stud 32 is that caused by the slight pressure of the spring 31.

While being placed for labor, the wrench parts are in substantially the position shown in Figure 3 and under labor as in Figure 1, at which time the direction of pressure is substantially as indicated by the line 33—33 85 which extends through the axis of the roll 24 and intersects the toothed face of the fixed jaw at a point substantially coincident with the line 34—34 in extension of the diameter of the work-piece. Thus, the pressure 90

upon the worm is toward the roll 24 and the engagement of the conical head 27 with the concaved face of the roll 24 insures a positive abutment for the worm and a tendency to rock the movable jaw and move its toothed face toward and secure a more rigid bite or hold upon the workpiece. Under labor there is substantially no pressure upon the worm supporting member 30. Reversal 10 of the movement of the wrench releases the grip upon the workpiece which is again secured as pressure is applied in the opposite direction.

The movable jaw while traveling from its 15 grip to its non-grip position and vice versa rocks on the fulcrum lug 19 which rides against the inner face of the fixed jaw 15 and maintains contact therewith.

The movable jaw may be adjusted toward 20 the fixed jaw either by rotating the worm or by merely applying pressure to the outer end thereof, in which case the teeth on the tail piece slide on the worm. In the opposite direction the jaw may be adjusted by rotation 25 of the worm or by drawing the jaw outwardly at the same time as the worm is pulled away from the tail piece, thus disengaging the worm from the teeth of the tail piece.

The worm as mounted is capable of movement axially in both directions, and is directly opposite the workpiece instead of upon the side thereof as is usual. These features insure greater flexibility of the jaw, add to the strength of the wrench, make the same more 35 compact, and permit the use of a movable jaw with a great capacity but comparatively short length.

One end of the worm is substantially conical, although in practice it has a slight curve, 40 the center of which is adjacent to the fixed jaw, preferably somewhere along the inner line thereof, as at 35. Thus, as labor is applied to the worm through the movable jaw, the engagement of the conical end of the 45 worm with the concaved face of the roll has a tendency to decrease the open space between the jaws and thus increase the grip of the movable jaw.

While it is desirable that the sides of the 50 conical end be slightly convexed, this is not essential to the operation of the device, as such sides may be straight, but it is believed the operation will be more efficient if convexed as indicated.

55 There are minor changes and alterations that may be made within my invention, and I would therefore have it understood that I do not limit myself to the exact construction herein shown and described, but claim all that 60 falls fairly within the spirit and scope of the appended claims.

What I claim as new is:

1. A wrench having a fixed jaw and a movable jaw, the latter moving upon a fulcrum 65 adjacent to the fixed jaw; a worm for actuat-

ing the movable jaw that is located opposite the opening between the jaws; and a support for the worm having endwise movement in both directions within a limited range.

2. A wrench having a fixed jaw and a movable jaw, the latter moving upon a fulcrum adjacent to the fixed jaw; a worm for actuating the movable jaw, located opposite the opening between the jaws; a support for the worm having endwise movement in both directions within a limited range; and an abutment against which the support member is guided in one direction. 70 75

3. A wrench having a head portion; a fixed jaw therein; a movable jaw therein; a worm within the head portion for actuating the movable jaw; and an abutment engaged by said worm while the jaws are under labor in contact with an article therebetween, the arrangement of the said jaws, actuating means and abutment being such that the strain and stress on the wrench under labor is in substantially a straight line that extends from a point on the fixed jaw where the article contacts therewith through the movable jaw and abutment, the extent of the area of the contact surface of said worm with the abutment being variable with the position of the worm. 80 85

4. A wrench having a head portion; a fixed jaw therein; a movable jaw therein; means within the head portion for actuating the movable jaw; and a rotary abutment engaged by said means while the jaws are under labor in contact with an article therebetween, the arrangement of the said jaws, actuating means and abutment being such that the strain and stress on the wrench under labor is in substantially a straight line that extends from a point on the fixed jaw where the article contacts therewith through the movable 90 95 100 jaw and abutment. 105

5. A wrench having a head portion; a fixed jaw therein; a movable jaw therein; means within the head portion for actuating the movable jaw located opposite the opening between the jaws; a support for said means having endwise movement in both directions and within a limited range held against lateral movement by the head portion and its endwise movement guided by a part connected 110 with the head portion. 115

6. A wrench having a head portion; a fixed jaw therein; a movable jaw having an intermeshing engagement with the head portion whereby its rocking movement is limited; means comprising in part a worm having engagement with the movable jaw for actuating the same; means for supporting the worm, comprising in part a support member mounted relatively to the head portion and providing a journal for the worm and having endwise movement in both directions derived from the action of the movable jaw; an abutment for directing such endwise movement in one direction; and yielding means between 120 125 130

the worm and its support that exerts an outward pressure on the worm.

7. A wrench having a head portion; a fixed jaw therein; a movable jaw therein having a fulcrumed lug thereon that contacts with the fixed jaw while the jaws are under labor in contact with an article therebetween; means comprising in part a worm for actuating the movable jaw; and a support for the worm having endwise movement in both directions within a limited range and in a path substantially parallel with that of the movable jaw, such endwise movement being derived from the action of the movable jaw, and in one direction guided by a fixed part on the head portion.

8. A wrench having a fixed jaw and a movable jaw; a worm for actuating the movable jaw; and an abutment for the worm, said worm having a conical end which by its engagement with the abutment tends to actuate the movable jaw so as to decrease the open space between the jaws.

9. A wrench having a fixed jaw and a movable jaw; a worm for actuating the movable jaw; an abutment for the worm; and a connection between the movable jaw and worm, whereby when the jaw is under labor it will impart endwise movement to the worm and the latter by reason of its engagement with the abutment will force the movable jaw so that the open space between the jaws may be reduced and thus increase the grip of the jaws on the workpiece.

10. A wrench having a fixed jaw and a movable jaw, the latter moving upon a fulcrum adjacent to the fixed jaw; a worm for actuating the movable jaw; and means for mounting the same whereby the movable jaw may maintain its same co-operative relation with the worm while the latter is moving upon the fulcrum.

11. A wrench having a head portion and a handle extending therefrom; a fixed jaw connected with the head portion, the engaging face of which is substantially parallel to the length of the handle; a movable jaw mounted within the head and fulcrumed adjacent to the fixed jaw; and means within the head for imparting movement to the movable jaw that may maintain its same relative position with the movable jaw while the latter is moving about the fulcrum.

12. A wrench having a head portion and a handle extending therefrom; a fixed jaw connected with the head portion, the engaging face of which is substantially parallel with the length of the handle; a movable jaw mounted within the head and fulcrumed adjacent to the fixed jaw, such means comprising a plurality of parts, two of which have endwise movement in both directions both as a unit and relatively to each other.

13. A wrench having a head portion; a fixed jaw; a movable jaw having teeth on the

face thereof distant from the open space between the jaws and fulcrumed for a rocking movement relative to the head portion; a worm for imparting endwise movement to the movable jaw; and means for maintaining the worm in contact with the teeth of the movable jaw during the said rocking movement and while under labor, comprising in part a support which derives an endwise movement from the movable jaw.

14. A wrench having a head portion; a fixed jaw; a movable jaw that rocks upon a fulcrum adjacent to the fixed jaw; a worm for imparting movement to the movable jaw toward and away from the fixed jaw; and means for supporting the worm whereby it will maintain a constant contact with the movable jaw irrespective of the relative position of the jaws and while the same are under labor or the movable jaw is moving upon its fulcrum, comprising in part a support that is movable in the head portion and is in contact with a fixed abutment which guides its endwise movement.

15. A wrench having a head portion; a fixed jaw; a movable jaw that rocks upon a fulcrum adjacent to the fixed jaw; a worm for imparting movement to the movable jaw toward and away from the fixed jaw; and means for supporting the worm whereby it will maintain a constant contact with the movable jaw irrespective of the relative position of the jaws and while the same are under labor or the movable jaw is moving upon its fulcrum, comprising in part a support that is movable in the head portion and having a shank and an angular face; and an abutment in engagement with said angular face and by reason thereof guides the support during its movement.

16. A wrench having a head portion; a fixed jaw; a movable jaw that rocks upon a fulcrum adjacent to the fixed jaw; a worm for imparting movement to the movable jaw toward and away from the fixed jaw; and means for supporting the worm whereby it will maintain a constant contact with the movable jaw irrespective of the relative position of the jaws and while the same are under labor or the movable jaw is moving upon its fulcrum, comprising in part a support that is movable in the head portion and is in contact with a fixed abutment which guides its endwise movement, said support having a shank portion and an offset portion substantially parallel therewith.

17. A wrench having a head portion; a fixed jaw; a movable jaw that rocks upon a fulcrum adjacent to the fixed jaw; a worm for imparting movement to the movable jaw toward and away from the fixed jaw; and means for supporting the worm whereby it will maintain a constant contact with the movable jaw irrespective of the relative position of the jaws and while the same are under

labor or the movable jaw is moving upon its fulcrum, comprising in part a support having a shank thereon and an offset portion upon one side of the shank in engagement with one wall of the fixed jaw, and an abutment in the head portion having contact with the support, the action of the movable jaw upon its fulcrum causing movement of the support which is transformed into an endwise movement through its engagement with the abutment.

10. In testimony whereof, I have hereunto affixed my signature.
